US0D1042136S

(12) **United States Design Patent** (10) **Patent No.:** **US D1,042,136 S**
(45) **Date of Patent:** **** Sep. 17, 2024**

(54) **BOTTLE**

(71) Applicant: **ALPINA PRODUCTOS ALIMENTICIOS S.A. BIC**, Sopo (CO)

(72) Inventor: **Álvaro Quintero Florez**, Sopo (CO)

(73) Assignee: **Alpina Productos Alimenticios S.A.S.—BIC**, Sopo (CO)

(**) Term: **15 Years**

(21) Appl. No.: **29/835,302**

(22) Filed: **Apr. 18, 2022**

(30) **Foreign Application Priority Data**

Oct. 19, 2021 (CO) NC2021/0013980

CLAIM

The ornamental design for a bottle, as shown and described.

DESCRIPTION

FIG. 1 is a perspective view of a bottle;

FIG. 2 is a front view thereof;

FIG. 3 is a side view thereof;

FIG. 4 is a top view thereof; and,

FIG. 5 is a bottom view thereof.

The broken lines depict portions of the bottle that form no part of the claim.

1 Claim, 5 Drawing Sheets
